UNITED STATES PATENT OFFICE.

WILLIAM THOMAS MASEK, OF DAVID CITY, NEBRASKA.

AUTOMATIC STOCK-FEEDING APPARATUS.

1,192,663.

Specification of Letters Patent. Patented July 25, 1916.

Application filed May 20, 1916. Serial No. 98,894.

To all whom it may concern:

Be it known that I, WILLIAM T. MASEK, a citizen of the United States, residing at David City, in the county of Butler and 5 State of Nebraska, have invented certain new and useful Improvements in Automatic Stock-Feeding Apparatus; and I do hereby declare the following to be a full, clear, and exact description of the invention, such 10 as will enable others skilled in the art to which it appertains to make and use the same, reference being had to the accompanying drawings, and to the letters and figures of reference marked thereon, which form a 15 part of this specification.

This invention relates to certain new and useful improvements in automatic stock feeding apparatus and the object in view is to provide a simple and efficient device of 20 this nature so arranged that at any predetermined moment the mechanism may be set to operate for feeding the stock.

The invention comprises various details of construction, combinations and arrangements of parts which will be hereinafter 25 fully described, shown in the accompanying drawings and then specifically defined in the appended claims.

My invention is illustrated in the accompanying drawings, in which:—

Figure 1 is an elevation showing the hay rack and grain boxes at their lowest normal positions. Fig. 2 is a similar view showing the hay rack and the boxes raised to dumping 35 positions. Fig. 3 is an enlarged detail sectional view showing the manner of mounting the racks and feed boxes.

Reference now being had to the details of the drawings by letter, A designates the 40 shaft of a building upon which the hoisting drums B are fixed, and C is a hinged rack upon which the hay or grain is adapted to be held and which is hinged at D to the manger in a convenient location to the point 45 at which the feed is to be dumped at a predetermined moment. Grain boxes, designated by letter F, are mounted upon said rack and their upper ends are opened and one edge, designated by letter H, projects 50 above the upper hinged edge of the rack for the purpose, as will be observed in Fig. 2 of the drawings, of extending over the edge of the manger when the rack is raised to dumping position. Hoisting cables, designated 55 by letter H', are fastened to the free swinging edge of the rack and passed over the

hoisting drums I. A cable N passes about a drum O upon the shaft A' and has a weight O' fastened thereto, a rope O² being secured to said weight O' and passing about 60 a reel O³ upon the shaft A and S is a handle which is fastened to a shaft and also to a ratchet wheel Q. A pawl Q' has connection with the lever T through the medium of a clevis T' and is adapted to hold the 65 ratchet in engagement with the ratchet wheel. A releasing hook, designated by letter W, is adapted to engage one end of the lever T and has a finger X designed to be actuated by any suitable clock mechanism or 70 electro-magnet Y.

In operation, the hay is placed upon the rack and feed within the boxes, when the rack and boxes are in the position shown in Fig. 1, the cable with the weight attached 75 being first wound up supporting the weight in an elevated position. The weight is normally held in its upright position through the medium of the hook engaging the lever which in turn causes the pawl to engage the 80 teeth of the ratchet wheel. The hook or trip W is actuated by the alarm mechanism of a clock at any predetermined moment which, when actuated, will be released from the lever T, allowing the ratchet to disengage 85 the ratchet wheel and which will permit the weight to rotate the shaft and wind up and cause the hoisting ropes H to wind up upon the drums and raise the racks to the elevated position shown in Fig. 2, in which 90 position the edges of the feed boxes will engage over the edge of the wall adjacent to the manger and dump the contents thereof into the latter.

By the provision of the apparatus shown 95 and described, it will be noted that a simple and efficient device is provided whereby stock may be fed at any hour by simply setting the alarm mechanism of the clock so that at a predetermined moment the trip may be actuated to allow the weight to cause the shaft to rotate and elevate the rack and feed boxes, allowing the same to dump by gravity into the manger.

What I claim to be new is:—

1. An automatic stock feeding apparatus comprising a rack and a manger to which the same is hinged, feed boxes having upper ends projecting above the hinged part of the rack and adapted to engage over the wall 100 of the manger when the box is elevated to a dumping position, a rotatable weight-actu- 110

105

ated shaft, drums thereon, ropes secured to the swinging edges of the rack and adapted to wind about said drums, a second shaft a ratchet wheel fixed to the latter, a reel rotating with the ratchet wheel, a rope winding about the reel, and a weight secured to the rope which passes about said reel, a pawl engaging the ratchet wheel, automatic means for releasing the ratchet wheel to allow the weight to cause the drums to rotate and elevate the shaft and feed boxes to dumping positions.

2. An automatic stock feeding apparatus comprising a rack and a manger to which the same is hinged, feed boxes having upper ends projecting above the hinged part of the rack and adapted to engage over the wall of the manger when the box is elevated

to a dumping position, a rotatable weight-actuated shaft, drums thereon, ropes secured to the swinging edges of the rack and adapted to wind about said drums, a second shaft a ratchet wheel fixed to the latter, a reel rotating with the ratchet wheel, a rope winding about the reel, and a weight secured to the rope which passes about said reel, a pawl engaging the ratchet wheel, a lever having connections with said pawl, and an automatically-operated trip engaging said lever.

In testimony whereof I hereunto affix my signature in presence of two witnesses.

WILLIAM THOMAS MASEK.
